UNITED STATES PATENT OFFICE

147,930

DESIGN FOR A CAMERA

Irwin Shayne, Chicago, Ill., assignor to Zenith
Camera Corporation, a corporation of Illinois

Application December 18, 1946, Serial No. 135,591

Term of patent 14 years

(Cl. D61—1)

To all whom it may concern:

Be it known that I, Irwin Shayne, a citizen of the United States, residing at Chicago, in the county of Cook and State of Illinois, have invented a new, original, and ornamental Design for a Camera, of which the following is a specification, reference being had to the accompanying drawing, forming part thereof.

Figure 1 is a top plan view of a camera embodying my new design;

Figure 2 is a side elevational view of such camera;

Figure 3 is a bottom plan view of the same device; and

Figure 4 is an end view looking from the right of Figure 2.

I claim:

The ornamental design for a camera, as shown.
IRWIN SHAYNE.
